UNITED STATES PATENT OFFICE.

JOHN M. HANSEN, OF PITTSBURG, PENNSYLVANIA.

HOPPER-CAR WITH FLUSH DOORS.

SPECIFICATION forming part of Letters Patent No. 727,621, dated May 12, 1903.

Application filed July 31, 1902. Serial No. 117,780. (No model.)

To all whom it may concern:

Be it known that I, JOHN M. HANSEN, a resident of Pittsburgh, in the county of Allegheny and State of Pennsylvania, have invented a new and useful Improvement in Hopper-Cars with Flush Doors; and I do hereby declare the following to be a full, clear, and exact description thereof.

My invention relates to metallic railway-cars, and more especially to that type of cars known as "hopper-cars." Its object is to improve cars of this type in details of construction, which will be hereinafter described and claimed.

In the accompanying drawings, Figure 1 is a longitudinal vertical section through one half of the car, taken partly on a plane passing between the center sills and the side of the car and partly on a plane passing through the longitudinal center of the car. Fig. 2 is a side view of the other half of the car. Fig. 3 shows at its upper portion a plan view of one half of the car and at its lower portion a plan of the car with the floor-plates removed. Fig. 4 is a transverse section on the line 4-4, Fig. 3; and Fig. 5 on its left-hand portion is an end view of the car and on its right-hand portion a transverse section on the line 5-5, Fig. 3.

My car is of that type having center sills only, there being no side sills, but the sides of the body of the car being formed as plate-girders, which assist in supporting the load. The underframe comprises center sills, body-bolsters, draft-sills, end sills, and appurtenant parts. The center sills 1 comprise channel shapes, preferably rolled channel-beams, placed parallel and with their flanges turned inwardly. They extend longitudinally through the central portion of the car-body and beyond the body-bolsters 2. These body-bolsters are of the built-up type, and each comprises a pair of web-plates 3, one on each side of the center sills and extending from the latter out to the sides of the car and preferably being tapered on their lower edges toward their outer ends. These web-plates extend a considerable distance above the center sills and have riveted thereto, near their upper edges, flanged bars, which are shown as angle-bars 4, one on either side thereof. Z or other bars may be used in place of the an-

gle-bars 4. These angle-bars extend continuously from side to side of the car and constitute the tension member of the bolster and 55 form the top of the bolster proper. The web-plates extend above the angle-bars 4 and have their upper edges bent at an angle corresponding to the slope of the floor of the body of the car, as shown at 5, and serve as supports for 60 the floor-plates, to which they are secured by rivets. Attached to the compression or lower side of the web-plates 3 are angle-bars 6, one on each face of said web-plates and extending from the ends of said plates to the center 65 sills. The compression side of the bolster is still further reinforced by a cover-plate 7, which extends from sections 8, riveted to the ends of the bolster continuously underneath the center sills to the opposite side. 70

Between the center sills at each bolster is a brace 9, preferably formed of cast metal, which is riveted to the center sills and bears upon the lower cover-plate 7. Each center brace is provided with a boss 10, provided 75 with a vertical hole through which the center pin passes. The center bearing-plate 11 is riveted to the bottom cover-plate 7. Above the center sills the web-plates 3 are united by plates 12, which have their upper edges 80 overlapped by the angle-bars 4 and their lower edges turned outward to form flanges 13, which rest upon the upper flanges of the center sills. Vertical angle-bars 14 are applied on each face of the web-plates 3, adjacent to the center sills, and have one of their flanges riveted to a web-plate and tie-plate 12 and their outer flanges riveted to the center sills. These serve to unite the body-bolster and sills and resist the shearing forces at 90 the adjacent sections of the body-bolster. Vertical angle-bars 16 are riveted to the web-plate on each face thereof, above or near to the body side bearings 17, and serve to stiffen the web-plates. At the ends of the bolsters 95 are similar vertical angle-bars 18, which also serve to stiffen the bolsters, while their projecting flanges serve as a convenient means for the attachment of side plates and sub side sills of the car. Horizontally-arranged 100 angle-pieces 19 are riveted to the outer faces of the web-plates 3 on each side of the center sills. To the horizontal members of these angle-pieces and to the top of the center sills

are secured connection or gusset plates 20, to which are connected the inner ends of horizontal diagonal braces 22, which extend outwardly to the corners of the car-frame, to 5 which they are secured by the gusset-plates 23.

The end sill consists of a Z-bar 25, extending continuously across the car and lying above and suitably secured to the draft-sills 26. The end sills are connected at the corners of the car 10 by means of the gusset-plates 23 and push-pole pockets 27 to the sub side sills 28. The latter are formed of Z-bars having their upper flanges turned inwardly and their lower flanges turned outwardly and extend from the 15 corners of the car to and are riveted to the ends of the body-bolsters. The draft-sills 26 are pressed channel shapes having their flanges turned outwardly. These draft-sills are of less depth than the center sills, and 20 their inner ends are overlapped and riveted to the outer faces of the webs of the center sills. Just beyond the ends of the center sills the draft-sills are connected by the cross tie-plate 31, the ends of which are interposed between 25 angle-bars 32 and the top flanges of said draft-sills. Rivets pass through the horizontal members of the angle-bars 32, the ends of the cross tie-plates 31, and the top flanges of the draft-sills. The vertical members of 30 the angle-bars 32 are riveted to the webs of the center sills. Draft-lugs 33 are attached by rivets in proper position to the webs of the draft-sills, the rear draft-lugs in some instances being also attached to the webs of the 35 center sills.

The outer ends of the draft-sills are reduced in depth, as shown in Fig. 1, and lie underneath the end sill 25. At the end of the car, at the center thereof, a hood or apron 35, made 40 preferably of a pressed steel plate, is riveted to the lower flange of the end sill 25 and secured to the ends of the draft-sills by short vertically-arranged angle-pieces 36. Lying beneath the draft-sill hood and between the 45 same and the draft-sills and riveted to both are the coupler-horn braces 37. A draw-bar carrier 38, made of a section of angle-bar, is supported by hangers 39, composed of flat pieces of plate metal riveted to the draft-sill 50 hood 35 and bolted to the draw-bar carrier. Between the draw-bar carrier and the lower flange of the draft-sill hood are placed the lower ends of the draw-bar liners 40.

The body of the car is formed of suitable 55 side plates, end plates, floor-plates, and supporting and stiffening parts. The side plates 44 are flat and trimmed to the proper shape. The end plates 45 are flanged at their lower edges, which flanges extend beneath and are 60 riveted to the floor-plates 46. These floor-plates have their side edges turned upward to form flanges 47, which abut against and are riveted to the side plates. The end plates extend to the side plates and are united there- 65 to by corner angle-bars 48, to the legs of which the side and end plates are riveted. These corner angle-bars extend down and are se-

cured to the underframe, so that they serve not only to unite the end and side plates, but act also as struts or corner-posts to transmit 70 a portion of the weight of the car-body and lading to the underframe. Extending along the tops of the side and end plates are angle-rails 50, whose vertical legs overlap, bear against, and are riveted to said side and end 75 plates. The vertical legs of the angle-rails may lie either on the outside or the inside of the side and end plates, and the horizontal legs may extend either outwardly or inwardly with respect to the car-body. The angle-rails 80 on the sides and ends of the car are united at the corners of the car by connecting cover-plates or top corner-gussets 51, which are riveted thereto. To the lower edges of the side plates between the body-bolsters are angle-rails 53, attached thereto in the same manner as those at the top of the car. The top and bottom angle-rails serve not only to increase the strength of the sides, which are practically plate-girders, and assist in supporting 85 the load, but also stiffen the same and prevent bulging or other lateral deformation of the sides, and the top angle-rails prevent the undesirable and dangerous exposure of the comparatively sharp edges of the side and end 90 plates. These angle-rails produce substantially the same finish as the flanges which are commonly formed on the edges of the side plates by pressing or bending; but their efficiency as lateral stiffeners is greater. 95

The side plates all lie in the same vertical plane, and they are united at their adjacent edges by trough-shaped stakes 54, to the flanges of which the side plates are riveted. These stakes are preferably of uniform cross-section throughout and lie between the horizontal members of the top and bottom angle-rails. To each side plate between the body-bolsters and about midway of said plate is 105 riveted a vertical angle-bar 55 to further stiffen the plate. Cover-plates 56 in the form of strips or welts are applied to the side plates inside the car opposite the stakes to increase the strength of the joints and to exclude the lading from the troughs of the side stakes. 110 Steps 57 are attached to the sides inside the car and serve to facilitate the passage of 115 trainmen over the car.

The floor-plates 46 slope from the ends of the car downwardly to the hopper-openings, 120 said floor-plates being supported on the flanged upper edges 5 of the web-plates 3 of the body-bolsters, as described. Between the body-bolsters and the ends of the car angle-bars 58 are attached to the under side of the 125 floor-plates in order to prevent them from sagging and to furnish a convenient means for attaching the outside floor-struts 59, and particularly the center floor-struts 60. The latter extend from the draft-sills 26 diagonally upward and are united to the angle-bars 58 by connecting-plates 61. They may be so shaped at their lower ends as to admit 130 of being riveted directly without the inter-

vention of any connecting-plate to the upper flanges of the draft-sills; but preferably they are riveted to the webs of said draft-sills and are so shown. The side floor-struts 59 are attached at their lower ends by means of connection-plates 62 to the Z-shaped sub side sills 28, and they extend upwardly in an inclined direction and have their upper ends riveted directly to the side plates 44 of the car and are also connected by means of the connection-plates 63 to the angle-bars 58. Braces 64 are attached to the sub side sills near the corner of the car and extend diagonally upwardly and inwardly and are secured to the angle-bar 58 by means of connecting-braces 65.

The hopper is formed by outside hopper-sheets 66, riveted to the sides of the car, and inside hopper-sheets 67, secured to the center sills. The outside hopper-sheets 66 are as near flat in shape and vertical in position as they can be made after being provided with a proper offset to pass over the lower side angle-rails. They are strengthened by means of angle-rails 68, riveted to the inclined end portion thereof, and horizontal angle-rails 69, riveted to the lower edges thereof, the latter angle-rails also serving as door-stops. The inside hopper-sheets 67 extend above and below the center sills and are so shaped above the center sills as to present inclined surfaces to the lading, so that the car will be self-clearing. Their upper edges are turned to form vertical angles 70, by means of which they are riveted directly to each other to form the central longitudinal hood over the center sills. Their bodies lie against the webs of the center sills and are riveted thereto. They likewise have at their inclined end portions the stiffening-flanges 71 and along their lower edges horizontal stiffening angle-bars 72, which also serve as door-stops. The inclined hopper-bottoms are strengthened by angle-rails 73, secured to the center sills and extending outwardly and secured to the outer hopper-sheets.

The hopper is divided into three compartments by two transverse diaphragms or partitions 75, which have for their primary object the tying together of the sills and sides of the car and the stiffening of the car in general. These diaphragms are comparatively deep, and each consists of two web-plates 76, one between the center sills and either side of the car. These web-plates are of considerably greater depth than the center sills and project below the same and also project above the longitudinal center ridge. Two angle-bars 77 are riveted to the lower edge of each pair of these web-plates, one on either side thereof, and extend continuously from side to side of the car. A similar angle-rail 78 is riveted to the upper edge of each pair of the web-plates and also extends continuously from side to side of the car. On the opposite faces of the web-plates, at their upper edges, is riveted a shorter angle-rail 79, which does not

extend entirely to the sides of the car, so as to permit the application of the oblique braces 80. The latter are preferably angle-bars riveted at their lower ends directly to the web-plates 76 and being secured at their upper ends to the side plates of the car by means of the connecting angle-pieces 81. There are two pairs of these oblique braces, one at each 75 diaphragm. The angle-bars at the lower edges of the diaphragm serve as door-stops, and the diaphragms as a whole are very deep and stiff and serve to support the center sills and to relieve the latter by transmitting a 80 larger portion of the load to the plate-girder sides of the car than would naturally come upon the latter.

The hopper is provided with six horizontally-arranged drop-doors 82, arranged in 85 pairs, there being a pair of oppositely-swinging doors for each compartment of the hopper and the doors being stiffened or reinforced by means of the angle-bars 84. By this arrangement three operating-shafts 85 are made to 90 control all of the doors. Each of these operating-shafts extends completely through the center sills and projects slightly beyond the outer face of one outside hopper-sheet, being there provided with a squared end for turning 95 the same and a toothed wheel 86 for the holding pawl or dog 87. These operating-shafts pass through the webs of the center sills, and near the central portion of each shaft, in the space between the center sills and underneath the 100 longitudinal hood or ridge, is secured one end of a chain 88, which is adapted to be wound thereupon. Each of these chains passes over a guide-sheave 89, mounted on a short idler-shaft journaled in bearings attached to the 105 inner faces of the webs of the center sills. The ends of the chains remote from the winding-shafts are attached to equalizing-levers 90, and the ends of the equalizing-levers are connected to the transverse door-angles by 110 means of links 91 and suitable eyebolts. By means of these equalizing-bars and links the doors of each pair can swing open in opposite directions, as shown, and a single operating-shaft can be employed for effectively closing 115 both doors of the pair.

What I claim is—

1. In a metallic hopper-car, the combination with the center and side sills, of transversely-arranged doors in the bottom of said car, and a transverse diaphragm or transom comprising a girder-like structure located between adjacent doors and secured to the center sills and sides of the car, one pair of said doors being hinged to said girder. 125

2. In a metallic hopper-car, the combination with the center sill, of plate-girder sides, transversely-arranged doors in the bottom of said car, and a transverse diaphragm or transom comprising a girder-like structure located between adjacent doors and secured to the center sill and sides of the car, one pair of said doors being hinged to said girder. 130

3. In a metallic hopper-bottom car, the com-

- combination with the center and side sills, of transversely-arranged doors in the bottom of said car, transverse diaphragms or transoms between said doors and secured to the center sill and sides of the car, one pair of said doors being supported from each of said diaphragms, and oblique tie-bars secured at their lower ends to said diaphragms and at their upper ends to the sides of the car.
- 10 4. In a metallic hopper-bottom car, the combination with the center sill and sides of the car, of a transverse diaphragm consisting of two web-plates, one on either side of the center sill, said web-plates extending above and below the center sill, flanged bars riveted to the web-plates near the top and bottom edges thereof and extending from side to side of the car, means for securing the diaphragm to the sides of the car and to the center sill, and
- 15 20 transverse doors in the car-bottom hinged to said diaphragm.

5. In a metallic hopper-bottom car, the combination with the center sill and sides of the car, of a transverse diaphragm consisting of two web-plates, one on either side of the center sill, said web-plates extending above and below the center sill, a flanged bar riveted to the lower edges of said web-plates and extending continuously from side to side of the car underneath the center sill, a flanged bar riveted to the upper edges of said plates and extending continuously from side to side of the car above the center sill, and oblique braces riveted to the web-plates and suitably secured to the sides of the car.

In testimony whereof I, the said JOHN M. HANSEN, have hereunto set my hand.

JOHN M. HANSEN.
